UNITED STATES PATENT OFFICE.

CHARLES G. ROSENHAUER, OF BROOKLYN, NEW YORK, ASSIGNOR TO UNDERWOOD TYPEWRITER COMPANY, OF NEW YORK, N. Y., A CORPORATION OF DELAWARE.

STENCILING MACHINE.

Application filed December 6, 1924. Serial No. 754,292.

This invention relates to stenciling machines, and more particularly to manually-operable ink-distributing means for the stencil-cylinder.

5 In rotary stenciling machines it is common to apply ink to the interior of the stencil-cylinder, the exterior of which is usually wrapped with an ink-pad, and overlaid with a stencil-sheet. The ink is distributed by brushing it around the interior surface of the cylinder-wall and into the foraminations, this operation being more or less inconvenient and likely to result in soiling of the operator's hands, as well as the 10 external parts of the machine or working materials, due to the necessity of handling the ink-container and ink-distributing implement, usually a brush.

The primary feature of this invention is 20 to enable an independent ink-distributing implement designed for hand-manipulation in the conventional manner to be supported upon a stationary stud-shaft or protection within the stenciling cylinder during operation of the machine, and easily and quickly removed bodily from its support for use.

A further feature is to enable the ink to be supplied to the interior of the cylinder from an external source by means of a hollow stud-shaft which may constitute the 30 stationary support for the rotatable cylinder at one end, the ink-distributing brush being constructed so that it is supportable on the hollow stud-shaft in telescopic relationship over the outer end thereof.

A still further feature is to simplify and improve the construction of hand-manipulable brushes for ink-distribution and other purposes; to enable easy disassembly of the 40 parts thereof for purposes of cleaning, replacement, adjustment or repair, and to afford provision for supporting the brush when not in use.

Other features and advantages will hereinafter appear.

In the accompanying drawings,

Figure 1 is a side elevation, partly in section, of a conventional type-stenciling machine, with the present invention applied thereto, the ink-distributing brush being supported in its inoperative position.

Figure 2 is a partial end view through the open end of the stenciling cylinder shown in Figure 1, partly in section.

55 Figure 3 is a perspective disassembly

view, showing the ink-distributing brush with the bristle-carrying head removed from the shell or holder.

The invention is illustrated in connection with a rotary stenciling machine of conventional type, which, in this instance, includes a stenciling cylinder having a foraminated wall 10 supported at one end upon a spider 11 rotatably mounted upon a stud-shaft 12 secured, as by the screw 13, within a collar 14 forming part of a frame standard 15 uprising from the machine base 16, the opposite end of the cylinder being open and having a rim 17 supported upon rollers 18 mounted in a yoke-frame standard 19, also 70 upstanding from the base 16, a rotating handle 20 being secured to the cylinder at the open end. The cylinder-wall in this instance has the usual outer ink-blanket 21, the rolled ends 22 of which are securable 75 in a longitudinal groove 23 by means of a clamp 24, and the cylinder is co-operable with a pressure roller 25 having opposite shaft-ends 26 journaled in bearings 27 provided at the sides of the frame-standards 15 80 and 19. The hub 28 of the spider 11 is formed with an annular groove 29 co-operable with the depending toe 30 of a spring-held latch 31, pivoted at 32 on the frame-standard 15, to hold the cylinder against 85 lateral movement on the stud-shaft 12 during operation of the machine, and to permit removal of the cylinder when desired.

According to the present invention, means are provided for mounting the ink-distributing implement upon a stationary shaft or projection within the cylinder, and for this purpose the stationary stud-shaft 12 projects partly into the interior of the cylinder, as seen at 33, and affords a means 90 of support for a manually-manipulable brush 34. The brush 34 preferably includes a shell or holder 35 having an integral handle 36 of conventional elongated form, which may be knurled on its outer surface as seen at 37, and a removable head 38 having bristles 39. The head 38 has an upstanding longitudinal rib 40 with a semi-cylindrical groove 41 formed in its upper portion, and when the head 38 is in place 105 within the shell 35 this groove 41 cooperates with a complementary portion 42 of a groove 43 formed within the shell 35 to provide a continuous longitudinal cylindrical bore or opening 44, in this instance 110

directed inwardly from the outer end of the head 38, parallel with the longitudinal axis of the handle 36, and substantially conformable to the outer configuration of the projecting portion 33 of the shaft 12, so that the brush may fit more or less snugly over the projecting end of the stud-shaft 12 practically enclosing the same in telescoping relationship, and be thus supported on the stud-shaft when not in use.

The bristle-carrying head 38 is insertable into and removable from the shell 35, the opposite sides 45 of the shell for this purpose being inturned to provide opposite longitudinal channels 46 co-operable with longitudinal angular guiding webs or extensions 47 projecting from opposite sides of the head 38 above the bristle-bearing portion, and the internal walls of the groove 43 of the shell 35 preferably extend from the complementary groove 42 to the plane of the top surfaces of the webs 47, so that the longitudinal groove 43 receives the rib 40. The head 38 is thus slidable into the shell 35, and in this instance is secured in place by means of thumb-screws 48 which extend through lugs 49 formed on the opposite lower side portions 45 and engage the edges of the webs 47. The head 38 may also be adjustably secured at different positions within the shell 35, so that the head projects beyond the end of the shell, thus facilitating its use in confined or restricted spaces, while, at the same time, increasing the effective length of the brush. The head may also be reversed, end for end, when the bristles at either end become worn to excess, and, when necessary, a new head may be substituted.

The brush may be otherwise constructed, but one essential feature of the invention, however, is the provision of the axial bore or opening 44 to telescope over the stationary support, which in this instance is the stud-shaft 12.

The shell 35 may be provided with an enlarged end or shoulder 65 to take the shock and wear incident to frequent, and possibly at times forcible, replacement of the brush on the stud-shaft 12 in abutting relation against the hub 28 of the spider 11.

The stud-shaft 12 in this instance is hollow, being formed with an axial bore 50 having communication at one end, by means of a connecting nipple 51, with the base 52 of a plunger-cylinder 53 provided in an ink-fountain or reservoir 54 mounted on a bracket 55 secured to the frame-standard 15. A plunger 56, normally resiliently held in inoperative position, as by a spring 57, is depressible by means of an external operating head or knob 58 to force a charge of ink, which normally settles in the bore 50, through the opposite end of the bore 50, where communication is afforded to the exterior of the stud-shaft through a cross port

59, passage through the cross port 59 being controlled by suitable means, as, for instance, a ball-valve 60 located in a coextensive larger diameter portion 61 of the bore 50. The ball-valve 60 is held to its seat 62 to close off the end of the bore 50, and normally restrain flow of ink through the cross port 59 by resilient means, preferably in the form of a coil-spring 63 held against the ball by a plug 64 which seals the outer end of the enlarged diameter bore 63, the plug 64 being threadable in the enlarged diameter bore 63, and thus serving to regulate the spring-pressure imposable on the ball-valve, the pressure being preferably of such degree as to be overcome by the force of the charge of ink displaced by the plunger 56, and permit the ball-valve to be unseated, yet sufficient to normally seal the bore 50. Details of the ink-reservoir referred to are more fully set forth in the co-pending application of Linden A. Thatcher, Serial No. 739,473, filed September 24th, 1924.

In the operation of inking the cylinder, the brush is grasped by the handle 36, and removed from the stud-shaft 12 by drawing it outwardly. The knob 58 of the ink-extruding mechanism is then depressed to cause a charge of ink to be deposited on the interior cylinder-wall, or directly onto the bristles, as may be desired, and the brush is manipulated in the customary manner to distribute the ink, after which the brush is replaced on the stud-shaft 12, where it may remain stationary and out of the way of the operator during operation of the machine.

With the above construction there is no necessity for the operator to come in contact with the ink, and the brush is always ready for use, the stud-shaft 12 acting as a combined cylinder-support, brush-holder and ink-supply conduit. When the brush is in position on the shaft the brush also functions as a cap or closure, so that no ink may leak through the cross port 59, and the work is thus not likely to be marred through undesirable leakage deposits of ink at any part of the cylinder-wall. Similarly, by enclosing the projecting end of the stud-shaft, the brush materially assists in preventing the ink at the cross port 59 from drying up and clogging the port, or causing the ball-valve to stick.

Variations may be resorted to within the scope of the invention, and portions of the improvements may be used without others.

Having thus described my invention, I claim:

1. The combination with a rotatable stencil-cylinder, of an interior central stud projecting from one end of the cylinder, and a bodily removable ink-distributing implement normally supportable on said stud.

2. The combination with a stenciling machine including a cylinder mounted to rotate about a stationary shaft which extends only partly into the cylinder, of an ink-distributing implement having an opening to receive an extending portion of said shaft to support said implement within the cylinder. 65
3. The combination with a stencil-cylinder mounted for rotation about a shaft extending only partly thereinto, of an ink-brush mountable on said shaft and bodily removable therefrom for independent manipulation. 70
4. In a stenciling machine, in combination, a cylinder, a shaft projecting into said cylinder for supporting the cylinder at one of its ends, and an ink-distributing brush telescopically supportable upon the projecting portion of said shaft, said brush being bodily removable from said shaft for manipulation independently thereof. 75
5. In a stenciling machine, the combination with a rotatable cylinder, of a fixed stud on which the cylinder rotates, said stud having an opening therein, an ink-reservoir in communication with said opening; and an ink-brush normally supportable on said stud, over said opening and removable to expose said opening. 80
6. The combination with a stenciling machine including a rotatable cylinder, an ink-reservoir, and an ink-brush, of a central hollow stud affording support for the cylinder, passage for the ink and support for the brush, said brush being bodily removable for operation independently of its support. 85
7. The combination with a stencil-cylinder mounted for rotation about a shaft extending only partly thereinto, of an ink-brush mountable on said shaft and bodily removable therefrom for independent manipulation, said brush including a handle, a shell and a removable bristle-carrying member. 90
8. The combination with a stenciling machine including a rotatable cylinder and an external ink-reservoir, of an ink-brush including a shell and a removable bristle-head, means for guiding and supporting said head within said shell, means affording an elongated opening between said head and shell, and a central hollow stud affording support for the cylinder, passage for the ink and support for the brush, said stud being receivable in said elongated opening to support the brush, and said brush being bodily removable from its support and manipulable independently thereof. 95
9. The combination with a stencil-cylinder mounted for rotation about a shaft extending only part way thereinto, of an independently operable ink-brush including a shell and a removable bristle-carrying member, and means for guiding the bristle-carrying member within the shell, said bristle-carrying member and shell having complementary grooves affording an opening in which the end of said shaft is receivable to removably support the brush on the shaft. 100
10. In a stenciling machine, in combination, a cylinder, a shaft projecting into said cylinder for supporting the cylinder at one of its ends, and an ink-distributing brush including a handle, a shell and a bristle-carrying member removably secured in said shell, said shell and bristle-carrying member having complementary grooves defining an opening to receive said shaft and telescopically support the brush upon the projecting end of said shaft. 105
11. In a stenciling machine, in combination, a cylinder, a shaft projecting into and affording support for said cylinder at one end, and an ink-distributing brush having co-operative members between which said shaft is receivable to support said brush in bodily removable relationship. 110
12. In a stenciling machine, the combination with a rotatable cylinder, of a fixed stud on which the cylinder rotates, said stud having an ink-passage, an ink-reservoir in communication with said ink-passage, and an ink-brush including a grasping handle, a shell and a bristle-head, said shell and bristle-head affording complementary provision to receive said stud to normally support the brush over said ink-passage and to permit bodily removal of the brush to expose said ink-passage. 115
13. An ink-brush and the like comprising a handle, a shell or body and a removable bristle-head, longitudinal guiding means co-operative between said head and said shell, and means for securing said head in position within said shell, said head and said shell having complementary grooves affording an elongated opening to receive a supporting stud. 120
14. An ink-brush and the like comprising a body, a handle and a removable bristle-head having guiding webs at opposite sides and a guiding rib between said webs, said body having grooved portions co-operative with said webs and rib to position the bristle-head within said body, and means for securing the bristle-head in place. 125
15. An ink-brush and the like comprising a body, a handle and a removable bristle-head having guiding webs at opposite sides and a guiding rib between said webs, said body having grooved portions co-operative with said webs and rib to position the bristle-head within said body, and means for securing the bristle-head in place, said bristle-head being reversible end for end. 130
